UNITED STATES PATENT OFFICE.

CAROLINE H. MOORHEAD, OF OCALA, FLORIDA.

DESIGN FOR A DISH.

Application filed July 19, 1924. Serial No. 10,187. Term of patent 14 years.

To all whom it may concern:

Be it known that I, CAROLINE H. MOORHEAD, a citizen of the United States, residing at Ocala, in the county of Marion and State of Florida, have invented a new, original, and ornamental Design for a Dish, of which the following is a specification, reference being had to the accompanying drawing, forming part thereof.

Fig. 2 is a plan view thereof.

I claim:

The ornamental design for a dish, as shown.

CAROLINE H. MOORHEAD.
